UNITED STATES PATENT OFFICE

THOMAS P. RYAN, OF WEBSTER, MASSACHUSETTS.

FASTENING FOR BOOTS, SHOES, &c.

SPECIFICATION forming part of Letters Patent No. 372,333, dated November 1, 1887.

Application filed March 2, 1887. Serial No. 229,474. (No model.)

To all whom it may concern:

Be it known that I, THOMAS P. RYAN, of Webster, in the county of Worcester, State of Massachusetts, have invented a certain new and useful Improvement in Fasteners, of which the following is a description sufficiently full, clear, and exact to enable any person skilled in the art or science to which said invention appertains to make and use the same, reference being had to the accompanying drawings, forming part of this specification, in which—

Figure 1 is an isometrical perspective view representing my improved fastener in use; Fig. 2, a vertical longitudinal section of the same, taken on line $x-x$ in Fig. 1; Fig. 3, a perspective view of the body of the fastener detached; Fig. 4, a like view of the tongue of the fastener detached, and Fig. 5 a vertical transverse section taken on line $y-y$ in Fig. 1.

Like letters of reference indicate corresponding parts in the different figures of the drawings.

My invention relates to that class of fasteners which are designed to take the place of buttons in fastening boots, shoes, gloves, &c.; and it consists in a novel construction and arrangement of parts, as hereinafter more fully set forth and claimed, the object being to produce a simpler, cheaper, and more effective article of this character than is now in ordinary use.

The nature and operation of the improvement will be readily understood by all conversant with such matters from the following explanation:

In the drawings, A represents the body of the fastener, B the tongue or fastener proper, and C D the flaps of the boot, shoe, or glove, 40 as the case may be, with which the fastener is used.

The body is preferably composed of sheet metal and is provided with two upwardly-projecting flanges or ears, $m m$, in which the tongue B is journaled, and with two downwardly-projecting flanges, ff , for securing the fastener to the flap C.

The flanges m are provided with corresponding holes, t , for receiving a pin, k , on which the tongue B is journaled, and with two inwardly-projecting protuberances, v . These protuber-

ances stand at the rear of a vertical line drawn through the pin k and are disposed near the lower ends of the flanges m , as best seen in Fig. 3. The tongue B is also preferably composed of sheet metal, and its body b is provided with two downwardly-projecting flanges, a , one at either side, in which there are holes l , for receiving the pin k . The flanges a are elongated and curved downwardly at the rear 60 of the pin k , each of them being provided with an outwardly-projecting protuberance, z , respectively, adapted to engage the protuberances v on the flanges m when the tongue is raised and lowered to open or close the fastener.

In the use of my improvement the body A of the fastener is secured by the flanges f to the flap C, opposite the slot y , and when it is desired to fasten the boot, shoe, or glove to 70 which the fastener is attached the tongue B is raised, passed through the slot, and bent down or depressed, as shown in Figs. 1 and 2.

In depressing the tongue the protuberances z are brought into engagement with the protuberances v , and as the tongue is forced down onto the flap C the rear or elongated portions of the flanges a are sprung inwardly, or yield to permit said protuberances to pass each other, and expand or spring outwardly as soon as 80 they have passed, thereby locking the fastener in a manner which will be readily obvious without a more explicit description.

All parts of the body A are formed integral, and may be struck up from sheet metal by 85 dies or other suitable mechanism, and the same will apply to the tongue B.

My improved fastener is specially adapted to that class of rubber overshoes known as "arctics" and for very heavy gloves, but may 90 be employed with nearly equal advantage on boots, shoes, and gloves of almost any description.

I do not confine myself to securing the body A to the flap C by means of the flanges or spurs f , as it may be secured by rivets or in any other suitable manner.

Having thus explained my invention, what I claim is—

1. In a fastener of the character described, 100 the combination of a body and a tongue, the body being provided with upwardly-project-

ing flanges or ears in which the tongue is journaled and with downwardly-projecting flanges for attaching it to the article with which the fastener is used, the tongue and body being respectively provided with protuberances which engage each other as the tongue is raised or depressed to lock the same, substantially as described.

2. In a fastener, the body A, provided with the flanges f_m , inwardly-projecting protuber-

ances v , and holes t , and the tongue B, having the elastic flanges a , provided with the outwardly-projecting protuberances z and the holes l , combined and arranged to operate substantially as shown and described.

THOMAS P. RYAN.
